UNITED STATES PATENT OFFICE.

HENRY A. WISE WOOD, OF NEW YORK, N. Y., ASSIGNOR, BY MESNE ASSIGNMENTS, TO THE AUTOPLATE COMPANY OF AMERICA, OF JERSEY CITY, NEW JERSEY, A CORPORATION OF NEW JERSEY.

SHEET-DELIVERY MECHANISM.

1,040,480.

Specification of Letters Patent.

Patented Oct. 8, 1912.

Application filed May 31, 1905. Serial No. 263,005.

To all whom it may concern:

Be it known that I, HENRY A. WISE Wood, a citizen of the United States, residing at New York, in the county of New York and State of New York, have invented a new and useful Sheet-Delivery Mechanism, of which the following is a specification.

The object of this invention is to provide a new and improved mechanism for delivering sheets, particularly adapted for use in connection with printing machines.

The particular object of the invention is to provide a new and improved way whereby a reciprocating carriage or carrier can act to turn over and deliver the sheet, so that if the mechanism is used in front of the impression cylinder of an ordinary printing machine, the traveling carriage will deliver the sheets with their last printed-side down. This new operation is accomplished by providing a gripping or seizing means independent of the carriage or carrier which engages and holds the edge of the sheet in front of the carriage as the same moves forward with the sheet thereon, which gripping or seizing means after it seizes the sheet moves out of the way down below the carriage, so that as the carriage moves forward the sheet will be turned over around the front end of the carriage and delivered under the carriage.

The carriage is preferably made in the form of a set of tapes, and during this delivery action the set of tapes is caused to run at such speed as to advance the sheet at the proper speed for this turn-over delivery, so that there will be no slip between the sheet and the tapes. This mechanism thus accomplishes the function of the usual fly delivery. This mechanism may be also advantageously employed in a so-called convertible delivery by adapting the reciprocating carriage to work in any of the ordinary ways to deliver the sheets printed-side up, and by providing means whereby said gripping or seizing mechanism may be thrown out of operation while the sheets are delivered printed-side up.

I have shown the carriage arranged to deliver the sheets printed-side up by simply causing the carriage-tapes to intermesh with the usual set of delivery tapes which run the sheet down from the impression cylinder on the plan described in my Patent No.

516,386, dated March 13, 1894, although, in some cases, I intend to use lifters or carriage fly-sticks in accomplishing the printed-side up delivery, as shown in my Patent No. 594,055, dated Nov. 23, 1897. The simplest arrangement, that is using merely the two sets of intermeshed tapes, is shown in this case for the purpose of illustration.

The invention can best be understood in detail by referring to the accompanying seven sheets of drawings, in which,

Figure 1 is a side elevation of enough of the mechanism to illustrate my invention. Fig. 2 is an elevation of the cam which is used to operate the gripping mechanism. Fig. 3 is a plan view of the reciprocating carriage. Fig. 4 is a side elevation of the same. Fig. 5 is a detail of one of the ratchet mechanisms used to actuate the carriage tapes. Fig. 6 is an end elevation of the gripping or seizing mechanism. Fig. 6^a is a detail of the means for guiding the sheet into the gripping or seizing mechanism. Figs. 7, 8, 9 and 10 are diagrammatic views illustrating the operation of the seizing or gripping mechanism. Figs. 11 to 14 inclusive are diagrammatic views showing the operation when the sheet is delivered printed-side up, and Figs. 15 to 18 inclusive are diagrams showing the operation when the sheet is delivered printed-side down.

Referring to the drawings and in detail, A designates the impression cylinder of an ordinary form of printing-machine.

B designates the usual set of delivery tapes which are trained around tape-rollers C and D, the tape-roller C being driven continuously in the usual way by gearing from the impression cylinder, as indicated by dotted lines in Fig. 1, so that the top surface of said tapes will run away from the impression cylinder. The sheets are directed out onto these continuously running delivery-tapes B by means of the usual stripper fingers S. These parts are of ordinary construction, and need not be described at greater length.

Brackets E—E are secured to the side-frames of the machine, and the delivery table F is held by said brackets and by standards G.

Extending up from the brackets E—E are supplemental brackets 10. Secured between the supplemental brackets 10 and the frame-

work projecting from the supports for the impression cylinder, are guides 11-11.

Rack-teeth 12 are cut on the under surface of the guide 11 which is at the gear side of the machine, shown in Fig. 1. A rack 13 is arranged between the frame projecting from the other impression cylinder support, and between the corresponding supplemental bracket 10, so that its teeth project upwardly 10 or oppositely relatively to the rack-teeth 12.

On the sides of the delivery table F are formed suitable guides 14.

15-15 designate the side-frames of the reciprocating or delivery carriage. These 15 side-frames have rollers 16-16 which run on top of the guides 11-11, and rollers 17-17 which run on the guides 14-14 on the delivery table. By this construction the carriage is capable of reciprocation away 20 from and toward the impression cylinder and over the delivery-table. Journaled in the front end of the carriage frames 15-15 is a tape roller 18. Journaled in the rear end of the carriage-frames 15-15 is a shaft 25 19 carrying a number of tape rollers 20. Suitable delivery-tapes 21 are trained between the tape-rollers 20 and the roller 18.

The carriage or delivery tapes intermesh with the delivery tapes as described in my 30 Patent No. 516,386 previously mentioned, and as shown in Fig. 3.

Rigidly secured on the shaft 19 are ratchet-wheels 22-220. Loosely arranged on the shaft 19 and meshing with the upper 35 rack 12 is a gear 23, and also loosely arranged on said shaft 19 is a gear 24 meshing with the lower rack 13.

The gears 23 and 24 are provided with pawls 25 to operate the ratchet-wheels. The 40 disposition of these gears, ratchet-wheels, and pawls is exactly the same on each side of the carriage, except that it will be noted that the gear 23 meshes with the upper rack, and that the gear 24 meshes with the lower 45 rack, whereby as the carriage is reciprocated, the oscillation of the gears 23 and 24 will be opposite relatively to each other.

The pawls 25 are provided with springs 26 to keep the same in operative position, 50 and with pivoted throw-out pieces 27. By moving a throw-out piece so that its end is pulled outwardly from the center, and by inserting a pin in the end of the same, and in a hole bored in the gear for this purpose, 55 the pawl controlled by the throw-out may be thrown out of operation.

As hereinafter described when the sheets are delivered printed-side up, the gear 23 and its ratchet mechanism is used, and the 60 gear 24 and its ratchet mechanism thrown out of operation; and when the sheets are delivered printed-side down, the gear 24 and its ratchet mechanism is used, and the gear 23 and its ratchet mechanism thrown out of 65 operation.

28 designates the cam-shaft of the machine, which is geared in the usual manner to make one turn for each cycle of operation. Fitted on the end of this cam-shaft is a crank-disk 29 which carries a crank-pin 30 which connects by pitman 31 to the end of 70 a lever 32 secured on, the end of a shaft 33 journaled in the brackets E. Secured on said shaft 33 are arms 34 which connect by links or pitmen 35 to the carriage frames 75 15-15, whereby the carriage is reciprocated to deliver the sheets.

The mechanism thus far described, with the exception of the gear 24 and its ratchet mechanism, constitutes a simple delivery 80 mechanism for delivering the sheets printed-side up on the delivery table.

The operation of this apparatus is shown in the sixth sheet of drawings.

The sheet first passes down onto the delivery tapes B, as shown in Fig. 11, which are continuously running. The carriage then moves away from the impression cylinder, as shown in Fig. 12, the carriage-tapes remaining stationary as the gear 23 turns in a direction to ratchet the pawl of the gear 23 around its ratchet-wheel 22. This movement will carry the sheet out over the delivery table, as shown in Fig. 13. Now as the carriage makes its backward or return stroke, as shown in Fig. 14, the carriage tapes 21 will be pulled from under the sheet by reason of the gear 23 turning in a direction to cause its pawl to engage its ratchet wheel and turn the shaft 19. By this operation the carriage tapes will peel from under the sheet, which will settle down on the delivery table and be delivered printed-side up.

As thus far described, the mechanism is 105 substantially the same as described in my Patent No. 516,386, and constitutes a mechanism for delivering sheets printed-side up.

The mechanism whereby the sheets may be delivered printed-side down will now be 110 described.

Journaled in the brackets E is a shaft 36 which carries a gripper or seizing mechanism. This shaft is oscillated by means of a cam 37 secured on the cam-shaft 28. The outline of this cam is shown in detail in Fig. 2, and the functions of its various surface will hereinafter be described. A lever 38 is pivoted on the side-frame and carries a roll 39 which engages said cam 37. This pivoted 120 lever connects by link 40 to an arm 41 mounted on the end of said shaft 36. A spring 42 is arranged on said link 40 between a block 43 secured to the side-frame, and a collar 44 adjustably secured on the link 40, whereby the spring is put under tension and the roll 39 normally kept in engagement with the cam. The lever 38 is provided with a hole 45 which registers with a hole 46 in the rear side-frame, whereby 130

by pulling said lever away from the cam and by inserting a pin in said holes 45 and 46, the said lever can be thrown out of operation. The lever is thrown out of operation when the sheets are delivered printed-side up, as previously described. 70
 5 Journaled in the supplemental brackets 10 is a shaft 47, mounted on which are a number of sheet-stoppers or directors 48 which are made out of light spring steel. The shaft 47 is oscillated by an arm 49 secured to the end thereof, which is connected by link 50 to a short arm 51 projecting from the hub of the arm 41. The function of these directors is to pat or direct the sheet down into the gripping mechanism as it seizes the sheet, as shown in Fig. 7, to prevent the end of the sheet from riding over the gripper mechanism. After these directors 15 guide the sheet into the gripping mechanism, they move up out of the way, as shown in Fig. 8. In some cases spring guiding strips 480 are arranged as shown in Fig. 6^a to guide the edge of the sheet from the 20 tapes B into the gripping mechanism. 75
 25 The gripper mechanism will now be described. 80

Secured to the shaft 36 just inside of the brackets E—E are arms 52, journaled in the 30 ends of which is a shaft 53 having a key-way. The shaft 36 also has a key-way cut therein as shown in Fig. 6. Secured inside the front bracket E is a segment 54, and secured on the shaft 53 is a co-operating segment 55, which segments are shaped so that as the shaft 53 is oscillated around the shaft 36, the shaft 53 will be turned on its own axis. The gripping mechanism is mounted on these two shafts 36 and 53, and 35 is made up of a plurality of individual grippers. As many of these grippers are used as the size of the press demands. These grippers are adjusted axially on the shafts 36 and 53, and held in place thereon by set-screws, whereby they may be set in any desired position, depending upon the character of the sheets which are to be delivered. These grippers are the same in construction, and one will now be described. The gripper 40 in the first place is made up of a double frame 56—56 which comprises two hubs keyed to the shaft 53, and depending arms 57—57. The hubs are connected together by a tongue 58 which forms the lower gripper-jaw, and which is provided with a stop 59. Arranged between the hubs of the gripper so as to fit loosely on the shaft 53 is the 45 upper jaw 60 of the gripper. It will be seen by this construction that the upper jaw 60 can turn on the shaft 53 relatively to the lower jaw 58, so as to open and close on the sheet. The upper jaw is provided with a projecting segment 61. The upper-jaw is kept normally closed by means of a spring 62 arranged on a rod 63 which is attached 85

to a small hub projecting from the rear of the upper gripper, and which passes through a block mounted on the trigger hereinafter described. A segment 64 meshing with the segment 61 is pivoted on a pin 65 secured between the gripper frames. This segment has a projecting arm 66. A trigger 67 is pivoted on a pin 68 also secured between the frames of the gripper. This trigger has a head or catch 69 which is adapted to engage the projecting end 70 of the movable upper jaw 60 of the gripper, as shown more particularly in Fig. 10. This trigger is provided with a depending arm 71 by which it may be released. A cam-block 72 is mounted on the shaft 36 for each gripper. Each cam-block can be adjusted on the shaft 36 to match the adjusted position of its gripper, and held in its adjusted position by a set-screw. Each cam-block has a projecting cam 73 to engage and operate the arm 66 of the segment, and a pin 74 to engage the arm 71 of the trigger which holds the movable jaw of the gripper open to release the same. This mechanism is operated entirely by the 90 oscillation of the shaft 36 through the cam 37. 90

The operation of the gripping or seizing mechanism in combination with the carriage, will now be described. 95

Suppose the gripping mechanism to have just closed on the end of the sheet, as shown in Fig. 7. The gripping mechanism is shown slightly raised above the front carriage roll 18, which is about the position at which the gripping mechanism takes the sheet as the delivery tapes are a little above the carriage-tapes. The operative surface of the cam 37 is divided into four sections *a—b—c—d*, in Fig. 2 for convenience of description. When the gripper mechanism takes the sheet as shown in Fig. 7, the roll engaging the cam 37 is in the position between the sections *a—b* of the cam, and the grippers are at their positions nearest the impression cylinder. Now as the cam turns to bring the section *a* thereof into operation, the shaft 36 will be oscillated from the position shown in Fig. 7 to the position shown in Fig. 8. This will cause the grippers to 110 revolve around the shaft 36 so as to swing to a position below the carriage tapes, and will cause the shaft 53 to revolve to turn the gripper-jaws, so that they will point toward the delivery table, as shown in Fig. 8. 115 As this movement of the grippers takes place, the carriage starts on its delivery movement toward the delivery table, but the grippers move in advance thereof so that the roller 18 of the carriage does not engage or 120 touch the gripper mechanism in any way. The grippers are turned toward the delivery table, so that no fold or crease will get in the sheet. Now as the carriage moves out over the delivery table the grippers will stand 125 130

stationary in the position shown in Fig. 8, by reason of the circular section *b* of the cam.

As previously described, when the sheets are to be delivered printed-side down, the gear 23 and its ratchet-mechanism is thrown out of operation, and the gear 24 and its ratchet mechanism thrown into operation. By reason of this adjustment, as the carriage 10 moves forward over the delivery table, the top of the delivery tapes will run forward in the carriage at practically the speed of the forward movement thereof, so that the sheet will be moved forward in the carriage, 15 and so that there will be no friction between the sheet and delivery tapes. As this movement takes place, the sheet will be turned over, as indicated in the diagrammatic Figs. 15 and 16, and when the carriage reaches 20 practically the end of its forward movement, the sheet will be completely turned over, so that when released it can settle down on the delivery table printed-side down, as shown in Fig. 17. Just before the carriage reaches its extreme forward movement, the section *c* 25 of the cam 37 comes into operation. The section *c* is slightly elevated relatively to section *b* of the cam. This slight difference will cause the shaft 36 to have a slight additional oscillation, that is, from the position shown in Fig. 8 to position shown in Fig. 9. The parts are so arranged that by reason of this additional oscillation, the arm 66 projecting from the segment 64 will engage the 30 cam 73 and oscillate the segments, opening the movable gripper-jaws which will be held open by the engagement of the triggers previously described. This will release the sheets from the grippers, and will allow the 35 same to be delivered printed-side down on the delivery table. Now as the carriage makes its return stroke toward the impression cylinder, the section *c* of the cam will hold the gripping mechanism in the position 40 shown in Fig. 8. As the carriage nearly completes its movement toward the impression cylinder, the section *b* of the cam will come into operation. This will swing the grippers to the position shown in Fig. 9, back to 45 the carriage, as shown in Fig. 10, the grippers still being open, and engaging the sheet which is at this time just in position to pass into the grippers. Just as this takes place, the pin 74 on each cam-block will engage the 50 projecting end 70 of the trigger which operates therewith, and by reason of the continued upward movement of the arm 41, will disengage the triggers and allow the 55 movable jaws of the grippers to seize the sheet, thus bringing the parts back to the position 60 shown in Fig. 7, when the cycle of operation will be completed.

The printed-side down delivery can well be understood from the diagrams shown in the last sheet of drawings.

It will be seen that all of the operations of the gripping and seizing mechanism come simply from the oscillation of the shaft 36.

In practicing the invention, the best results are obtained by timing the crank-pin which reciprocates the carriage, so that the carriage will be about on its reverse toward the impression cylinder when the sheet is fully out on the delivery tapes, and in so 75 setting the crank-pin when the sheets are delivered printed-side up that the carriage will be at the extreme of its travel toward the impression cylinder before the sheet is fully out on the delivery tapes. To obtain 80 this adjustment, the crank-disk 29 is loosely mounted on the cam-shaft 28, and is held in position by a bolt 75 projecting from the cam 37, and extending through a circular slot 76 cut in said crank-disk. A nut 77 is 85 threaded on the end of the said bolt, and by this construction the crank-pin can be set relatively to the shaft, and the desired adjustment of the reciprocating carriage obtained. 90

The foregoing delivery mechanism can also be well arranged for "slip-sheeting". To accomplish this, the carriage-frames are extended up and provided with bearings 78. A light frame 79 is provided with tongues 80 which can be dropped into slots in these bearings. This frame is made up of cross rods and bars extending longitudinally between the cross-bars. Slip sheets can be placed on top of this frame, and can be used 100 no matter whether the device is set to deliver the sheets printed-side up or printed-side down. In operation with this slip-sheeting device, the operator stands at the end of the press, and as the carriage reaches 105 the end of its forward stroke, the operator lifts the top slip-sheet up over the stops which hold the sheets in place, and holds the same so that as the carriage withdraws or moves toward the impression cylinder, the 110 slip-sheet will be left in position to settle down on the last delivered printed sheet. In this way the printed sheets may be separated from each other by slip-sheets, which is desirable sometimes when high-class color or 115 other work is to be run.

The details and arrangements of parts for practicing the invention herein shown and described may be greatly varied by a skilled mechanic without departing from the scope 120 of my invention as expressed in the claims.

Having thus fully described my invention, what I claim and desire to secure by Letters Patent is:-

1. In a sheet delivery mechanism, the combination of a reciprocating carriage, a set of tapes mounted therein, means for driving the tapes on the forward movement of the carriage, gripping mechanism for engaging the end of the sheet and moving and 125

holding the same below the tapes so that as the tapes advance, as the carriage moves forward, the sheet will run on the tapes and be turned over.

5 2. In a sheet delivery mechanism, the combination of a reciprocating carriage, means for operating the carriage, a set of tapes arranged therein so that sheets will be delivered printed side up thereby, means for driving the tapes on the forward movement of the carriage, a seizing or gripping mechanism mounted in front of the carriage, and means for throwing the same into operation so that the same will seize and hold the front 10 edge of the sheet below the tapes, whereby as the carriage advances, the sheet will be run forward and turned over.

15 3. In a sheet delivery mechanism, the combination of a reciprocating carriage, a gripping or seizing mechanism arranged independently of the carriage so as to come in front of the same, means for turning the gripping mechanism down out of the way of the carriage after it has engaged the sheet, 20 directors arranged above the carriage and adapted to press the sheet into the bite of the grippers, and means for moving the directors out of the way as the carriage advances.

25 4. In a sheet delivery mechanism, the combination of a reciprocating sheet carrier, means for advancing the sheet beyond the edge of the carrier, a gripping and seizing means independent of the carrier for engaging and holding the front edge of the sheet in front of and below the carrier, mechanism for operating the gripping and seizing means capable of being disconnected from operation, and means for adjusting 30 the advancing mechanism so that it can act to deliver the sheet upon the rearward movement of the carriage.

35 5. In a sheet delivery mechanism, the combination of a carrier having a set of 40 tapes for advancing the sheet, means for driving the tapes on the forward movement of the carriage, a delivery table, and a gripping and seizing means independent of the carrier located in position to hold the forward 45 end of the sheet at the rear of the delivery table and below the carrier so that the forward movement of the carrier will advance the sheet relatively to the carrier and so that the sheet will be turned over for 50 delivery.

55 6. In a sheet delivery mechanism, the combination of a reciprocating carriage, a set of tapes mounted therein, two ratchet mechanisms for actuating said tapes, a gripping or seizing mechanism arranged in front of the carriage, and means for throwing said ratchet mechanisms and gripping mechanism into and out of operation, arranged so that when the one ratchet mechanism is used, 60 the sheets will be delivered printed-side up, 65

and so that when the other ratchet mechanism and the gripping mechanism are used, the sheets will be delivered printed-side down.

7. In a sheet delivery mechanism, the combination of a reciprocating carriage, an oscillating shaft carrying arms, a shaft journaled in said arms, means for oscillating this shaft in its arms, and gripping mechanism mounted on the shaft, whereby said gripping mechanism will be turned out of the way of the reciprocating carriage and additionally turned to point toward the way the sheet is delivered. 70

8. In a sheet delivery mechanism, the combination of a reciprocating carriage, an oscillating shaft 36, arms 52 mounted thereon, a shaft 53 journaled in said arms, means for oscillating the shafts 36 and 53 and gripper mechanism mounted on the shaft 53. 80

9. In a sheet delivery mechanism, the combination of a reciprocating carriage, an oscillating shaft 36, arms 52, a shaft 53 journaled in said arms, means for oscillating the shafts 36 and 53, and gripper mechanisms mounted on the shaft 53 and adjustable 90 axially thereon.

10. In a sheet delivery mechanism, the combination of a reciprocating carriage, an oscillating shaft 36, arms 52 mounted thereon, shaft 53 journaled in said arms, means for oscillating shaft 36, segments 54 and 55 for oscillating shaft 53 in the arms 52, and gripper mechanisms mounted on shaft 53. 95

11. In a sheet delivery mechanism, the combination of a reciprocating carriage, an oscillating shaft 36, arms 52 mounted thereon, shaft 53 journaled in said arms, means for oscillating the shaft 53 in the arms 52, gripper mechanisms mounted on the arms 52, springs for closing the grippers, and triggers for holding the grippers open. 100

12. In a sheet delivery mechanism, the combination of a reciprocating carriage, a shaft 36, a cam connected to oscillate the same, gripper mechanisms carried by said shaft, means for opening the grippers, triggers for holding the grippers open, and cam-blocks, the parts being arranged so that the gripping mechanism will be operated by 110 oscillation of shaft 36.

13. In a sheet delivery mechanism, the combination of a reciprocating carriage, an oscillating shaft 36, arms 52 mounted thereon, a shaft 53 journaled in said arms, means for oscillating the shaft 53, springs tending normally to close the movable jaws thereof, segments for opening said jaws, triggers for holding the jaws open, and cam-blocks mounted on the shaft 36 for operating the 120 segments to open the grippers and for releasing the triggers.

14. In a sheet delivery mechanism, the combination of a reciprocating carriage, a set of tapes mounted therein, two loosely 130

- mounted wheels in said carriage, an upper rack which one wheel engages, and a lower rack which the other wheel engages, ratchet mechanisms, means whereby the ratchet mechanisms may be thrown into and out of operation, and a gripping or seizing mechanism arranged in front of the carriage, whereby the sheets may be delivered printed-side up or printed-side down.
- 10 15. In a sheet delivery mechanism, the combination of a reciprocating carriage, a set of tapes arranged therein, a gripping or seizing mechanism arranged independently and in front of the carriage, means for re-

ciprocating the carriage, and means for actuating the gripping or seizing mechanism to deliver the sheets one side up, said gripping and seizing mechanism being capable of being thrown out of operation so that the sheets may be delivered the other side up. 15
20

In testimony whereof I have hereunto set my hand, in the presence of two subscribing witnesses.
